PROCESS OF THERMALLY DECOMPOSING
HYDROCARBONS

Charles J. Strosacker and Harold S. Kendall,
Midland, Mich., assignors to The Dow Chemical
Company, Midland, Mich., a corporation of
Michigan

No Drawing. Application October 31, 1930,
Serial No. 492,618

1 Claim. (Cl. 260—170)

The present invention relates to the thermal decomposition or cracking of hydrocarbon oils, particularly to processes wherein gaseous products rich in olefines are chiefly produced, and has regard more especially to improvements in the materials from which the cracking retorts are made, whereby increased yields of olefines and other advantages are secured.

In present processes for making gaseous olefines by passing hydrocarbon oil vapors through a heated zone maintained at a temperature between 700° and 1000° C., various types of cracking retorts may be used, but in general a tubular retort is preferred for facilitating a rapid heating of the oil vapors and the maintenance of uniform temperature conditions. In the past the retorts employed for the cracking have been made of iron or steel, including certain special steel alloys such as alloys containing chromium, etc. We have now found that a materially greater rate of production of gaseous olefines may be maintained in a retort of any given dimensions and at the same cracking temperature if the heating surfaces of such retort are composed of a nickel-chromium alloy, or nickel-chromium-iron alloy, in which nickel is the principal constituent. We are aware that it has been proposed in U. S. Patent 1,646,349 to carry out the thermal decomposition of hydrocarbons in contact with an alloy of iron and chromium and also in U. S. Patent 1,703,949 with an iron-chromium alloy containing a minor percentage of nickel. The present invention represents a material advance in the art of cracking hydrocarbon oils over the processes of the aforementioned patents. The invention, then, consists of the steps and means hereinafter fully described and particularly pointed out in the claims, the following description setting forth in detail a preferred embodiment of the invention constituting, however, but one of the various ways in which the principle of the invention may be used.

A preferred procedure for carrying out the invention consists in general in vaporizing a hydrocarbon oil, e. g. petroleum or a petroleum distillate such as kerosene, etc., at a temperature preferably below that at which any material cracking thereof to products of lower molecular weight takes place, for instance, between about 300° and 500° C.; passing the vapors under reduced pressure through a retort, preferably a tubular retort, of a nickel-chromium or nickel-chromium-iron alloy in which such vapors are contacted with metallic surfaces heated to a temperature between about 700° and 1000° C.; and separating the gaseous products from undecom-

posed oil vapors. As alloys suitable for the purpose are understood those containing 50 per cent or more of nickel as the principal constituent, together with relatively smaller amounts of chromium, with or without iron as a third major component. The presence of iron may be advantageous for practical purposes to lower the cost of the alloy, improve its mechanical working properties or for other reasons. Smaller amounts of other metals may also be present as minor or incidental components, e. g. copper, manganese, etc. In general, suitable alloys are those designated in the trade as "Nichrome", the composition of which may vary within the following limits:—

	Per cent
Nickel	50 to 80
Chromium	10 to 25
Iron	4 to 30

As an example of the improvement realized in practicing the invention, comparative figures are given showing results of cracking kerosene in a tubular retort using tubes of a chrome-nickel iron alloy and of nichrome, respectively. The composition of the chrome-nickel iron alloy was approximately; Cr—18 per cent; Ni—8 per cent, balance chiefly iron; that of the nichrome; Ni—60 per cent, Cr—12 per cent, balance chiefly iron. The tubes were 2 inches in diameter and 6 feet long. The temperature in the cracking zone was held between about 800° and 870° C., and oil was fed at a uniform rate of 11 gallons per hour under an absolute pressure of 5 to 15 inches of mercury. In the table the comparative figures of the average results are shown:—

	Cr-Ni iron	Nichrome
Per cent kerosene cracked	67.9	80.5 95
Cu. ft. gas produced per hour	590	815
Per cent ethylene in gas	32.1	31.1
Per cent higher olefines in gas	32.4	28.5
Per cent total olefines in gas	64.5	59.8
Cu. ft. ethylene produced per hour	191	254
Cu. ft. total olefines produced per hour	384	486

While the percentage of total olefines in the gas produced with the nichrome tube is somewhat lower, the large increase in percentage of oil cracked and in total volume of gas produced far more than offsets this. There is a net gain of 105 26.5 per cent in the total olefines, and of 33 per cent in the ethylene produced, the ratio of ethylene to total olefines being appreciably increased. The foregoing example, while giving a comparison of the results obtained using tubular retorts of 110

the two different metals, does not imply any limitation upon the conditions for carrying out the cracking operation other than may be specified in the appended claim. In particular the 5 rate of feed of kerosene may be varied if so desired, and we have found that a somewhat higher rate of feed gives further advantages, as shown in the following table, the examples therein having been taken from runs made with the same 10 nichrome tubular retort as in the example above, and operated at the same temperature.

	Cr-Ni iron	Nichrome
15 Rate of feed, gal. per hour	12.0	16.3
Percent kerosene cracked	77.2	70.5
Cu. ft. gas produced per hour	900	1,032
Per cent ethylene in gas	33.5	31.9
Per cent higher olefines in gas	30.6	32.1
Per cent total olefines in gas	64.1	64.0
Cu. ft. ethylene per hour	302	330
20 Cu. ft. total olefines per hour	577	661

It is seen that a higher rate of feed results in a slightly reduced percentage of cracking but a 25 higher output of gas and total olefines and a slightly increased percentage of olefines in the gas.

Other advantages accruing from the use of nichrome tubes or retorts are the resistance to oxidation of the same, which gives increased life 30 in service, and also the very small amount of

carbon formation within the tubes. Although a tubular form of retort is preferred, the invention comprehends also the use of other forms of retorts fabricated from nickel-chromium or nickel-chromium-iron alloys of the class described, the novelty thereof not being dependent upon the shape, form, nor dimensions of the retort. Likewise it is sufficient to provide a lining of nichrome or equivalent alloy in a retort constructed of iron, steel or other common material, the essential 85 feature of the invention being to conduct the cracking operation in contact with or in the presence of surfaces of nichrome or similar alloy.

Other modes of applying the principle of our invention may be employed instead of the one 90 explained, change being made as regards the process herein disclosed, provided the step or steps stated by any of the following claims or the equivalent of such stated step or steps be employed.

We therefore particularly point out and distinctly claim as our invention:—

The process of producing olefines which comprises thermally decomposing a hydrocarbon oil at a temperature between 700° and 1000° C. while 100 in contact with surfaces of an alloy containing 50 to 80 per cent nickel, 10 to 25 per cent chromium and 4 to 30 per cent iron.

CHARLES J. STROSACKER.
